H. G. BLUMBERG,
INTERNAL COMBUSTION ENGINE,
APPLICATION FILED DEC. 13, 1918.

1,368,881.

Patented Feb. 15, 1921.

UNITED STATES PATENT OFFICE.

HAMILTON G. BLUMBERG, OF SAN ANTONIO, TEXAS.

INTERNAL-COMBUSTION ENGINE.

1,368,881.

Specification of Letters Patent. Patented Feb. 15, 1921.

Application filed December 13, 1918. Serial No. 266,563.

To all whom it may concern:

Be it known that I, HAMILTON G. BLUMBERG, of San Antonio, in the county of Bexar and State of Texas, have invented certain new and useful Improvements in Internal-Combustion Engines; and I do hereby declare the following to be a full, clear, and exact description of the invention, such as will enable others skilled in the art to which it appertains to make and use the same.

My invention relates to internal combustion engines and particularly to valve mechanism for controlling the inlet of the gaseous fuel and the exhaust of the burnt gases, and the object of the invention is to provide an improved and simple arrangement of valves in compact form and in such manner as to eliminate the dead air space commonly present in valve casings of internal combustion engines, as well as to provide improved mechanism for operating the valves. The subject matter is an improvement upon the valve mechanism shown, described and claimed in Letters Patent No. 1,304,735 issued to me May 27, 1919.

The invention includes a main valve for controlling communication to and from the combustion chamber and valves governing the ports of entrance of the gaseous fuel and the exhaust of the burnt charge, these latter valves being of the slide type and so arranged in the valve casing as to eliminate dead space, thereby effecting a saving in gas, since there is no pocketing of the latter between the inlet valve and the main valve when the latter closes for the compression and explosion and which gas would co-mingle with the exhaust gases and be forced out therewith on the exhaust stroke of the piston. For the purpose of insuring exact timed action of these three valves I have provided a single cam the eccentrics of which are so arranged as to simultaneously effect the opening of the main valve and the exhaust valve, the eccentric governing the latter permitting it to close while the main valve is held open, and the eccentric of the cam governing the inlet valve causes it to open while the main valve is still held open, both these valves, the main and the inlet simultaneously closing, all three valves being held closed during the compression and explosion strokes of the piston.

In the accompanying drawings, Figure 1 is a vertical sectional view of a cylinder head

equipped with my improved valves, showing the position of the latter on the intake stroke of the piston. Fig. 2 is a vertical sectional view on line 2—2, Fig. 1, looking in the direction of the arrows. Figs. 3 and 4 are detailed views of the actuating cam.

Referring to the drawings, 1 designates a cylinder head having a centrally disposed port 2 terminating in branched inlet and outlet passages, 3, 4, respectively, the centrally disposed port 2 being controlled by a main valve 5 of puppet form, the stem of the valve passing through an upwardly extending portion 6 of the head, where appropriate connection is made with an actuating arm A for moving the valve against the tension of a coiled spring 7 seated against the top of the casing and a washer or head 8 on the stem.

The inlet manifold 12 and the exhaust manifold 13 are located on opposite sides of the upwardly extended portion 6 of the cylinder head, and a port 14 of the former and port 15 of the latter are controlled by slide valves 16, 17, respectively. These valves are fitted within recesses in the manifold casing immediately adjacent the portion 6 of the head, being firmly seated against the wall of the manifold.

Each valve has an upwardly extending stem 18 projecting through the manifold casing and provided at its outer end with a washer or head 19 between which and the manifold casing is a coiled spring 20 which normally tends to hold the valve elevated and in position to close the port of its respective manifold. These valves are moved against the tension of their springs by arms B and C, the arm B engaging the stem of the valve 16 and the arm C that of the valve 17. These two arms and the arm A connected with the stem of the main valve are actuated by a cam mechanism to be herein-after described. In order to insure a close contact of the valves 16 and 17 with their respective seats, I provide pairs of pins 25, 26, preferably of bronze, which are slidably fitted within transverse bores in the portion 6 of the head, the outer ends of one pair bearing against the valve 16 and those of the other against the valve 17. The inner ends of these pins are beveled and those of complementary pairs are contiguous. Short vertically disposed rods 27 have their lower ends pointed and, under the control

of springs 28 encircling the upper ends of the rods and fitting in recesses of the portion 6 of the head and held in such recesses by plates 29 secured to the head, are adapted 5 to engage the beveled ends of the pins 25, 26 to at all times force the pins outwardly.

Any preferred form of cam mechanism may be employed to actuate the valves hereinbefore described which will insure the 10 simultaneous opening movement of the exhaust and main valves, the continuance of the open position of the main valve while the exhaust valve is being closed and while the inlet valve is opening and a closing of 15 the main valve simultaneously with the closing of the inlet valve. A preferred embodiment of such mechanism is illustrated in the drawings and includes a single cam having its three eccentricities in different vertical 20 planes as well as on different radii. The eccentric 30 engages the L-shaped rod 31 to which is secured the arm B which actuates the inlet valve 16. The eccentric 32 engages a similar L-shaped rod 33 secured to the 25 arm C which is in engagement with the stem of the valve 17. Eccentric 34 is adapted to move the L-shaped rod 35 whose arm A actuates the main valve 5. It will be observed that the formation of these eccentricities and 30 the location with respect to each other is such that when the eccentric 32 starts to act on the rod 33 the eccentric 34 will also begin to act on the rod 35 so that both the exhaust valve 17 and the main valve 5 will 35 simultaneously open to permit exhaust of any products in the combustion chamber. The circumferential area of the eccentric 34 being greater than that of eccentric 32 it will hold the rod 35 down while the valve 40 17 is closing and will hold this rod down and the valve 5 open until the eccentric 30 has moved the rod 31 downwardly and fully opened the inlet valve 16 after which both the main valve 5 and the inlet valve 16 will 45 close together, all valves remaining in closed position during the compression and expansion strokes of the piston.

I claim as my invention:

1. In an internal combustion engine, a cylinder having an explosion chamber at 50 one end, and a single port forming the inlet and exhaust for said chamber, a main valve controlling said port, inlet and exhaust manifolds communicating with said port, said manifolds having each a valve 55 seat in juxtaposition to said points of communication with said port, slide valves adapted to close said points of communication, pairs of pins bearing against said valves to hold them to their seats, spring 60 actuated rods for controlling the tension of said pins, and cam mechanism for actuating all of said valves to cause said main valve and exhaust valve to simultaneously open, said exhaust valve to close while said main 65 valve is held open, said inlet valve to open while the main valve is open, and said main and inlet valves to simultaneously close.

2. In an internal combustion engine, a cylinder having an explosion chamber at 70 one end, and a single port forming the inlet and exhaust for said chamber, a main valve controlling said port, inlet and exhaust manifolds communicating with said port, said manifolds having each a valve seat in 75 juxtaposition to said points of communication with said port, slide valves adapted to close said points of communication, pairs of pins bearing against said valves to hold them to their seats, said pins having beveled 80 extremities, spring actuated rods having pointed ends bearing upon said beveled extremities to hold said pins with relation to said valves, and cam mechanism for actuating all of said valves to cause said main 85 valve and exhaust valve to simultaneously open, said exhaust valve to close while said main valve is held open, said inlet valve to open while the main valve is open, and said main and inlet valves to simultaneously 90 close.

In testimony whereof, I have signed this specification.

HAMILTON G. BLUMBERG.
